UNITED STATES PATENT OFFICE.

JOSEPH O. BALDA, OF NEWARK, OHIO, ASSIGNOR TO A. H. HEISEY & COMPANY, OF NEWARK, OHIO.

DESIGN FOR A PITCHER OR SIMILAR ARTICLE.

Application filed February 15, 1922. Serial No. 715. Term of patent 14 years.

To all whom it may concern:

Be it known that I, JOSEPH O. BALDA, a citizen of Hungary, residing at Newark, in the county of Licking and State of Ohio, have invented a new, original, and ornamental Design for Pitchers or Similar Articles, of which the following is a specification, reference being had to the accompanying drawing, in which a view, in side elevation, is shown of a pitcher embodying the form, shape, and design in its physical embodiment.

What I claim is:—

The ornamental design for a pitcher or similar article, as shown.

JOSEPH O. BALDA.
